10 Claims. (Cl. 175—294)

1
This invention relates to means for permanently or intermittently supervising, testing, indicating and controlling the condition of contact between electrically conductive parts which are required to maintain intimate contact between them, and this without interruption of the operation of the devices or installations which these parts belong to.

This invention is applicable to contacts between contacting parts of any kind provided they are capable of conducting electrical energy, but it is particularly valuable in application to systems traversed by a working current i. e. a current doing useful mechanical, electrical or chemical work and liable to be disturbed or injured by fundamentally imperfect or suddenly or gradually deteriorating contact between two contacting current-carrying parts.

It is one of the objects of this invention to provide means whereby the operator of an electrical installation is warned of any imperfection or deterioration of contact in the circuit as soon as it arises, thus enabling him to remedy the defect before it has resulted in injury to the installation or in material loss of energy or processed material.

Instead of leaving it to the operator to remedy the defect, the diminution or the temporary interruption of current feed may be effected by means of devices which are activated or thrown in automatically whenever the deterioration of contact exceeds a predetermined limit.

As is well known to those skilled in the art, electrical conditions in contacts or other parts of electrical circuits, and more especially in heavy current circuits, vary in dependency on the influences exerted on them by the media in which they are operating. The oxygen or the moisture in the air will cause the formation of an oxid layer on a contact surface. Dust, oil or grease may form insulating coatings thereon. Oxidation may also occur through the action of heat. Loosening of mechanical connections may occur through many causes. In all such cases there results a rise of resistance to the passage of current.

According to this invention the variations in this intermediate resistance are rendered visible or audible in indicating or alarm devices, or are utilized to activate switches, permanently con-

nected to the contacting parts to be protected or supervised, while these parts are traversed by the working current. In any case the attendants or operators are thus warned and induced to remedy the defect or, if necessary, to temporarily throttle or cut out the current.

All variations of the intermediate resistance between contacting surfaces result in corresponding variations of the voltage drop at these surfaces. This is particularly true in the case of high current installations such as are present in electric melting furnaces operating with currents up to and beyond 50,000 amp. Obviously in such cases any unnoticed rise of the intermediate resistance in a contact may cause very considerable injury to the parts and losses of energy and/or metal. Frequently the electrodes are overheated to the extent of becoming incandescent, arcs may form between the electrodes and their holders, the bus bars may be heated to melting temperature etc. In most cases the defect that is at the root of all this, will not or cannot be detected in time and the installation may be out of working for many hours or even days.

Hitherto no means have been available for preventing with certainty and automatically the damage arising from such causes.

Numerous devices are on the market for measuring the specific resistance of solid conductors, but these devices are not suitable for the purpose here in view, i. e. the detection of imperfect contact between contacting parts traversed by a working current. For, in contrast to the resistance in solid conductors, the intermediate resistance between contacting parts varies owing to circumstances such as set out above and also to the intensity of current. If this resistance is ascertained or measured under current conditions considerably below those of the normal working current, the results may be deceptive. Therefore in these measuring devices, all of which operate with a separate current, frequently as high a current intensity is used as possible, but since they must be portable, the intensity is limited for technical reasons to a few hundred amperes. Obviously now it is impossible, with so low a current, to correctly measure contact resistances in apparatus, for instance electric melting furnaces, traversed by many thousand

amperes. But quite apart from this technical limitation, these devices are only used to measure resistances in a de-energized equipment. They do not indicate all conditions arising during actual operation, when vibrations or temperature influences or some other circumstances may altogether change the resistance at the contacts, sometimes followed by arc formation and eventual melting down of contacting parts.

In contrast to these existing methods of resistance measurement, the present invention enables me to test the conditions of contact in the equipment while it is operating and traversed by the working current, I can provide for a continuous testing and measuring and an automatic signalling of contact conditions and variations, and I may also provide means for automatically throttling or cutting out the current. In every case I utilize the circumstance that any deterioration of contact is accompanied by a corresponding change of voltage drop at the contact. In cases where the amperage is subject to considerable variation, I prefer to use a measuring instrument indicating the quotient of the prevailing system current and voltage, for instance a cross-coil instrument, which is known to indicate directly the resistance, for indicating the disturbance.

While as a rule the working current will be used to actuate the indicating instruments, alarms or switches, I may also use a separate current for this purpose without in any way impairing the result, which will be the same as that obtained with the aid of the working current, since I employ the separate current while the working current flows.

For instance, if a separate direct current is used in an alternating current system to indicate the condition of contacts in accordance with my invention, the direct current voltage drop arising from the intermediate resistance exactly corresponds to the actual intermediate resistance formed at this moment by the entire working current. Thus the separate direct current used for testing and indicating these variations furnishes the same picture of the conditions of operations, as would be obtained with the aid of the full working current of thousands of amperes. This method may be particularly advantageous whenever it is desired to eliminate the induction effect exerted on the test (measuring) results. In all cases the operator, without being required to take action for this purpose, is continuously furnished full information regarding any deterioration of the contacts during operation and is thus enabled to prevent in time injury to, or destruction of, the equipment.

I will now proceed to describe by way of example some characteristic applications of my invention in order to thereby show that it will be useful in widely different fields of utilization of electrical energy. The examples hereinafter described with reference to the drawings should not in any way be considered as limiting the scope of my claims to the individual means or combinations of means nor to the particular uses and applications shown and described. For there exists hardly any form of electrical installation in which my invention could not be applied with advantage. Certain features of my invention disclosed herein but not claimed are claimed in my copending application Serial No. 55,605, filed October 20, 1948.

Throughout the drawings affixed to specification and forming part thereof, similar numerals

are intended to designate similar parts. In the drawings

5 Fig. 1 is a diagram of an alternating current system comprising an electrical melting furnace 5 with an electrode mounted in a holder, in combination with means according to this invention for continuously supervising, indicating and controlling the variations of contact between these parts during operation, making use of the working current for effecting this indication and control.

10 Fig. 2 is a similar view of a direct current system in combination with means for supervising contact conditions in the bus bars by means of 15 the working current.

Fig. 3 is a diagram of an alternating current system with a bus bar contact controlled by means of a separate direct current.

20 Fig. 4 is a similar view of a direct current system in combination with means for supervising a bus bar contact by means of a separate alternating current.

25 Referring to the drawings and first to Fig. 1 this is a diagram of connections of a circuit feeding alternating current of high intensity through the lead 1 to the electrode holder 2 of the electrode 3 of an electric melting furnace and through it to the body 5 of molten metal. The condition of contact between the electrode and 30 the holder is supervised and controlled continuously, while the furnace is in operation, or while the supply circuit is connected to a useful load, by providing a measuring instrument which may be permanently connected in the circuit and at 35 any time indicates to the operator whether the contact is good or requires improving. To this end two wires 8 and 9, connected to the holder and the electrode at 6 and 7, respectively, lead to the primary winding 11 of the voltage transformer 10. The potential of the secondary transformer winding 12 is transmitted by wires 13 and 14 to the bridge rectifier 22, while on the other side a wire 15 leads to the contact piece 147 of a small controller whose normal position 40 is marked by the letter A, where the current from contact piece 147 passes through the contact segment 15, connecting wire 16, segment 17, contact piece 153 and wire 21 to the other side of the rectifier 22 and from one side of the rectifier 45 through wires 23, 143, 24 to the voltage coil 25 of the measuring instrument (cross-coil ohmmeter) 26, from the other side through wire 163, contact 27 and wire 28 to the series resistance 29 allowing adjustment to different measuring 50 ranges, and from this resistance through the brush 144 and wire 31 to the second end of the voltage coil 25 of the measuring instrument.

55 The electrode 3 is supplied with current through wire 164, the primary winding 33 of the current transformer 32, whose secondary winding 34 is connected on one side to the rectifier 42 by way of wire 35, ammeter 36 and wire 41, while the other winding is connected to the rectifier by the wire 43. From this rectifier the wire 60 47 leads to one end of the adjustable shunt 48, while a wire 49 connects the rectifier to the brush 50 of this shunt, whose ends are connected on one side through wires 165, 55 to one end of the current coil 53 of the cross-coil instrument, on the other side through wires 51, 52 to the other 65 end of this coil.

70 Since the cross-coil ohmmeter directly indicates the ratio of potential and current, the resistance can be read directly on its scales. Adjustable series resistance 29 and adjustable shunt

48 are provided for the purpose of adapting the instrument to various conditions in different installations. Since this ohmmeter merely indicates the ratio of potential and current, the amperage fed to the furnace is immaterial to the result. As long as the intermediate resistance between the furnace electrode and the holder remains constant, its pointer 161 will remain stationary. Whenever the contact should deteriorate by a loosening of the electrode in the holder or from other causes the pointer will move at once, and if the deterioration of contact reaches a certain limit, the pointer will establish contact between the terminals 54 and 59 of a signalling circuit which comprises the current source 58, one terminal of which is directly connected through wire 57 to the relay 56, while the other terminal is connected to the relay through wire 60, closed contacts 59, 54 and wire 166. Relay 56 will now close the contact 64 and thereby excite, with the aid of current supplied by the current source 65, the optical or acoustical signalling device 66. Thus the operator, unless he had ascertained the deterioration of contact by observing the position of the pointer of the ohmmeter, is warned at once of the danger threatening the furnace and its contents. If he should not heed the signal or if he should be absent, the signalling instrument will, by means of a time-relay, resistance and circuit breaker (not shown) connected to it by the wires 67, 68 first throttle the current supply and thereafter cut it out altogether. An excess voltage which may arise occasionally is provided for by a switching relay 130 connected in parallel to the voltage coil 25 of the cross-coil instrument by a wire 131 leading to the regulating brush 144, the other wire 132 being connected between wires 143 and 23. Any excess voltage in the potential coil of the instrument will cause the relay 130 to open the contact 27. Further means serving as a protection against excess voltage will be described farther below.

In the case of extremely low voltage it is advisable to ascertain from time to time whether the contacts in the testing circuit are perfect. To this end a rotatable controller is provided with a separate alternating current source feeding a low tension transformer 70 with a resistance 13 regulating the current output of the secondary winding 12 which is connected by the wire 14, amperemeter 75 and wire 76 to the contact piece 155, while on the other side the wires 78 and 79 lead to the contact piece 156. Between the wires 14 and 78 a voltmeter 77 is connected for measuring the voltage output.

When the controller is turned into the first testing position B, current will flow from one terminal of the low tension transformer 70 through contact piece 155, segment 82, wire 83, segment 84, contact piece 148, wire 149 and wire 13 to one end of the winding 12 of the voltage transformer 10. The other end of winding 12 is connected to the source of current by means of the contact piece 156, segment 87, wire 86, segment 85, contact piece 147 and wire 14. Hereby this winding 12 is excited and a voltage is induced in the other winding 11, which, if all the contacts are in good order, is short circuited through wire 9, contact 7 of the electrode 3, wire 8 and the contact 6 of the electrode holder 2. The deflection of the pointer of amperemeter 75 at a predetermined deflection of the voltmeter 77 then allows to readily ascertain whether the contacts 7 and 6 at the electrode and its holder are in order. If they should be oxidized, a mate-

rially lower current will pass through. In every installation the empirically determined values are ascertained by tests. If the deflection of the amperemeter is found to be too low, the voltage 5 at the regulating resistance 13 is increased until the instruments show that good contact is re-established.

By setting the small controller to the position C, the other side of the circuit of the voltage coil 10 is then tested. To this end one pole of the voltage transformer is connected with one side of the rectifier 22 by way of contact piece 155, segment 88, wire 89, segment 90, contact piece 150 and wire 21. The other pole is connected with the other side of the rectifier 22 by way of contact piece 156, segment 93, wire 92, segment 91, contact piece 148, wire 149 and wire 141.

By applying a predetermined voltage and varying it any deflection of the pointer 161 of the cross-coil instrument 26 will be noticed, while the current coil 53 is fed by the working current through the voltage transformer 32.

The check-up device hereabove described can be used also with advantage for testing any other 25 part of the apparatus.

While Figure 1 illustrates an electrode and electrode holder of a furnace, I wish it to be understood that this is merely one example out of the great number of points of contact in an alternating current installation which can be controlled and protected in the manner here described.

Figure 2 illustrates the application of the principle underlying this invention to a direct current system, the testing device being again traversed by the working current. Here the contact between two bus bars 201, 202 shall be tested.

The greater part of the equipment including the wiring from the cross-coil instrument and its 40 voltage coil up to the contact 27 and wire 143 is exactly the same as in Fig. 1. Contact 27 is connected by way of wires 206 and 205 to the contact 203 on bus bar 201. The other side of the voltage coil is connected to the other bus bar 45 202 through wires 143 and 218, contact piece 213 (the controller being in the normal operating position A), segment 212, wire 211, segment 210, contact piece 209, wire 207 and contact 204.

This inner connection of the current coil 53 50 up to the adjusting shunt 48 is also the same as in Fig. 1. One end of the shunt 48 is connected through the wires 233, 232 to one end of the shunt 231 which is inserted in the lead 298 to bus bar 201. The brush 50 is connected through 55 wire 230, contact piece 225, segment 224 (the controller being in the position A), wire 223, segment 222, contact piece 221, wire 220, ammeter 297 and wire 219 to the second terminal of the shunt 231.

This system functions exactly like the one illustrated in Fig. 1. Here also any excessive rise of the intermediate resistance will cause the pointer of the cross-coil instrument to be deflected so far as to close the contact 54 and 59, 60 whereby the signal device 66 is actuated. The protection against excess voltage is the same as in Fig. 1 and here also two positions of the check-up device are shown, in which the contacts are tested.

This example comprises a separate source of direct current 234 with a voltage divider 235, (check up device in position "B"). One pole is connected to wires 242, 243, contact piece 246, segment 252, wire 253, segment 254, contact 70 piece 209 and wire 207 to the contact 204 on bus

bar 202. The other pole from the separate direct current source (battery) is connected through contact piece 241, segment 247, wire 248, segment 249, contact piece 250 and wires 251, 205 to the contact 203 of bus bar 201.

Here, as in the system shown in Fig. 1, the deflections of ammeter 238 and the voltmeter 291 of the separate source of current will show whether there exists an intimate contact in the tested system. Here also, if necessary, the voltage will be increased until the contacts are re-established.

In the position C the connection leading to the shunt 231 is tested. Since this is done in exactly the same manner as explained with reference to position B, there is no need for going into the details of this connection.

Obviously here also the check-up device can be used for testing any other contacts in the system.

Fig. 3 illustrates an alternating current system comprising bus bars, the contacts between which are placed under supervision of devices supplied with separate direct current.

This direct current circuit comprises a low-tension source of direct current for instance a battery 303, feeding direct current through the regulating resistance 304, wire 305, ammeter 306 and wire 307 to the bus bar 301. From the other pole of the battery current flows through wire 308, shunt 309, wire 310, regulating inductive resistance (choking coil) 311 and wire 312 to the other bus bar 302.

From shunt 309 testing wires 317, 318 lead to the adjustable shunt 48 and its brush 50. The shunt is further connected, in exactly the same manner as in the examples described above, to the current coil 53 of the cross-coil instrument 26. The voltage coil 25 of this instrument is connected, exactly as in the previous examples, up to the contact 27 and wire 143. This wire is connected through wire 316 to bus bar 302, while contact 27 is connected through the regulating choking coil (inductive resistance) 314 and wire 313 to the other bus bar 301.

The regulating resistance 304 regulates the direct current used for testing. Its amperage is indicated by the ammeter 306. Shunt 309 feeds current to the current coil 53 of the cross-coil instrument.

The drop of potential, caused by this direct current, at the point of contact of the two bus bars is fed through the wires 315, 316 to the voltage coil 25 of the cross-coil instrument.

The entire system operates exactly as described before with reference to Figs. 1 and 2.

Obviously the working current (alternating current) passing through the two bus bars at the contact point will suffer a drop of potential also. In order to prevent this drop of potential of the alternating current from influencing the testing apparatus, the two choke coils 311 and 314 mentioned above are provided. They offer a high inductive resistance to the passage of the alternating current, while allowing the direct current to pass through freely, and therefore exact tests can be obtained during operation with the separate direct current without paying regard to the presence of alternating current. The choke coils 311 and 314, thus serve as isolating units for in effect isolating or substantially separating the measuring circuit from the load circuit, viz., the direct-current circuit from the alternating-current circuit.

The drop of potential of the separate direct

current is exactly proportional to the intermediate ohmic resistance offered to the entire alternating working current. Even in those cases where the direct current intensity only amounts to a small percentage of the alternating working current intensity, a correct picture of the intermediate resistance is obtained.

This mode of testing this resistance offers particular advantages in all cases where the effects of an inductive resistance at the contact point to be controlled shall be eliminated. When using alternating current for the tests, this inductive resistance might make the drop of potential appear much higher than would correspond to the purely ohmic resistance. The use of separate direct current eliminates this phenomenon and also offers the advantage of allowing to ascertain the presence of fairly good contact even before operations are started, while any variation of the intermediate resistance during operation is indicated also.

The separate source of direct current, such as the battery, can be charged up from the alternating current system with the aid of a corresponding low-tension transformer and a rectifier.

In Fig. 4 a direct current system is illustrated in which the testing is done at a pair of bus bars during operation with the aid of separate alternating current. An alternating current source supplies current through a low-tension transformer 404, whose secondary winding 406 is connected at one end to the regulating resistance 407, wire 408, ammeter 409, and through wire 410 to the bus bar 401. From the other end of the secondary transformer winding 406 current flows through wire 411, primary winding 33 of the current transformer 32 and wire 412 to the second bus bar 402.

The secondary winding of the current transformer 32 is connected to the current coil of the cross-coil instrument through the rectifier in the same manner as has been explained with reference to Fig. 1, as can easily be ascertained from Fig. 4, where the same parts are marked with the reference numerals already used in Fig. 1.

The drop of potential at the point of contact caused by the alternating current is passed on to the primary winding 11 of the voltage transformer 10 through wires 413, 414. The secondary winding 12 carries this voltage through the rectifier 22 to the voltage coil of the cross-coil instrument in exactly the same manner as in Fig. 1.

For the sake of simplicity the check-up device has been omitted in Figs. 3 and 4.

The ammeter 409 indicates the amperage used in this testing.

The drop of potential of the working direct current at the bus bar contact occurs parallel to that of the alternating current, but this drop of potential of the direct current cannot influence the test results. The transformers 10 and 32 transform and thereby transfer the drop of potential of the alternating current and the intensity of this current onto their secondary windings and further to the cross-coil instrument. In contradistinction thereto the transformers prevent the direct-current drop of potential in the network from reaching the secondary windings. Thus here, as in Fig. 3, the tests with separate alternating current are not disturbed by the working current. In this instance the transformers 10 and 32 serve as the isolating

units for separating the measuring circuit from the load circuit. If precise preservation of the instrument transformer ratio, and highly accurate indications are desired, suitable blocking devices such as condensers or rectifiers connected in opposition to direct-current flow may be interposed in the circuits of the input windings 11 and 33 of the instrument transformers, as will be well understood by those skilled in the art.

This mode of testing the contacts will be particularly advantageous in cases where the contacts are liable to frequently deteriorate materially or to even open altogether, since instead of the full network voltage for instance of 110 or 220 volt, only a few volts from the separate source of current can reach the test instrument and it is easier to protect the instruments from injury by this low voltage.

To also illustrate the use of separate alternating current for testing the contacts in an alternating current system does not appear to be warranted since the combination of apparatus will be the same as shown in Fig. 4.

For instance in a system of this kind operating with many thousands of periods, separate alternating current of 25 or of 60 periods may be used for measuring and indicating the variations of intermediate resistance. The inductive resistance of the measuring transformers which are designed for a low number of periods, oppose so high an inductive resistance to the high frequency alternating current that any influence exerted by the alternating working current is paralyzed. Exactly as in the system described with reference to Fig. 4, this mode of testing the intermediate resistance would offer the advantage that the testing apparatus would be better protected against excess voltages arising in consequence of great deteriorations of the contacts. Normal types of measuring devices designed for 60 periods could be used in such cases.

In contradistinction to ordinary measuring methods, the present invention is not primarily concerned with the actual magnitude of the ohmic resistance of a contact, the main purpose being to let the operator know when a deterioration has taken place which renders it necessary for him to take preventive action.

If a protective equipment according to this invention is used in connection with an alternating current system operating with very high current intensities, for instance in a circuit comprising an electric melting furnace or a high-duty transformer, it may happen that the testing and signalling lines must be located in the vicinity of very strong magnetic fields whereby they will be exposed to a high induction effect.

In order to paralyze this effect, the wires will be arranged as closely together as possible in order to keep the induction effect as uniform as possible. It may nevertheless happen that the induction will not be exactly the same in two wires leading to a protective device, and in such a case an additional voltage may be induced in the measuring wires, which may even amount to a multiple of the normally measured voltage drop. In order to eliminate this induction effect I prefer connecting with each other the ends of each pair of measuring wires and to connect to their opposite ends leading to the switchboard a sensitive alternating current voltmeter or a moving coil voltmeter with a rectifier with or without a voltage transformer, or some other sufficiently sensitive indicating instruments. If in a

normal test the two wires show a difference of inductive potentials, one of them is reduced or increased in length until its induction potential is equal to that of the other wire and is thus compensated. The indicating instrument is then replaced by the regular testing device.

Obviously the cross-coil instruments shown and described throughout the specification may be replaced by other suitable measuring or indicating instruments, for instance a wattmeter or an ammeter in combination with, or without, a series resistance.

The examples of applications of this invention in the protection of electrical systems show that this protection can be obtained with the aid of the working current in direct and in alternating current systems. The invention is further applicable to conductors and to entire parts of a network. The devices to be used for protection may be stationary or portable and of a merely indicating (signalling) or recording type and may be provided with amplifying devices. The term "electrical system" is employed in the description and claims to designate an electrical installation under load or energized. For example, the term refers to electrical installations where the current from the network, generator, battery, etc., or any other source of power is taken with the main purpose of producing work or converting electrical energy to another form of energy, for instance, conversion into mechanical work or heat, or another form of electrical magnetic or electromagnetic energy as in high frequency induction heating. The term "electrical system" as herein used, excludes purely measuring circuits where the only source of current applied is a separate source used with the purpose of making measurements without performing work in some manner as explained above.

Of the equipments to be protected by means of this invention the following are particularly noteworthy: bus bars, connections in motors, generators, transformers, fuse connections, cable connections within machines and apparatus, electric melting furnaces etc. and in a general way power stations, transformer stations, steelworks, chemical works, electric railway systems, electro-chemical installations for the recovery of metals such as copper, nickel, silver etc., but also electrical cooking, heating and illuminating installations.

While the principal and most important field of application of this invention is the protection of electrical systems, i. e. systems traversed by a working current, it will be apparent that the invention can be used also with similar advantage in the protection of devices, apparatus and machinery of non-electrical character in which two separate electrically-conductive parts are jointed together and held in contact with each other by mechanical means such as rivets, screw bolts or the like or by soldering, brazing or welding. In most types of working machines, prime movers etc. screw bolts jointing two contacting parts may become loose during operation under the influence of vibrations or the like. In aircraft certain parts such as bracing members may be loosened through the impact on the ground when landing.

The safe operation of electrical installations on board of ships, more especially warships may depend on the automatic supervision of the contacts by means of this invention. In all these cases a low tension current traversing the joint

or contact will be affected by the rise of the intermediate resistance resulting from such loosening, and this rise of resistance can be rendered visible or audible during operation with the aid of my protection devices.

The control effected according to this invention includes, besides the changes in the ohmic resistance, also the changes in the inductive (apparent) resistance in alternating current systems.

The term "every essential magnitude" is intended to include all resistance changes occurring between the normal state of the contacts and a degree of deterioration which involves danger to the functioning of the system.

I wish it to be understood that I do not desire to be limited to the exact details disclosed in the specification and drawings, for obvious modifications will occur to persons skilled in the art.

I claim:

1. A protective arrangement for rendering perceptible predetermined degrees of changes of contact conditions in an electrical system having a circuit traversed by load current including a pair of conductors in contact, said protective arrangement comprising in combination with such contact and connections for connecting said contact to a useful load and for causing passage of load current through such contact, a device responsive to ratio of voltage to current having a movable element, a translating device actuated by movement of said movable element, said ratio responsive device including a voltage winding and a current winding, connections bridging the voltage winding across said contact and adapted to be connected permanently, and connections having a serial relation to said contact for energizing the current winding in proportion to the current traversing said circuit and adapted to be permanently connected.

2. A protective arrangement for rendering perceptible predetermined degrees of changes of contact conditions in an electrical system having a circuit traversed by load current including a pair of conductors in contact while connected to a useful load, said protective arrangement comprising in combination with such contacting conductors and connections for causing passage of load current through such contact between the contacting conductors, an instrument responsive to voltage-current ratio having a movable element, said ratio responsive instrument including a voltage winding and a current winding, connections from the voltage winding across said contact, and connections having a serial relation to said contact for energizing the current winding in proportion to the current traversing said circuit.

3. An electrical system comprising in combination a current-carrying circuit and a protective arrangement therefor, said circuit including a pair of conductors in contact, the contact impedance of which is subject to variation, and a useful load supplied by said circuit, said protective arrangement comprising apparatus for indicating the magnitude of such contact impedance, said apparatus comprising in combination with such contact and connections for causing the passage of alternating-current through such contact a voltage-current ratio responsive instrument including a voltage winding and a current winding, connections including a rectifier operatively connecting the voltage winding across said contact, and connections including a second rectifier having a serial relation to said contact for energizing the current winding in proportion

to the alternating current traversing said contact.

4. In an electrical system including a circuit traversed by a load current and containing an impedance element, the impedance of which is subject to variation, an apparatus for indicating the magnitude of such impedance, said apparatus comprising an electrical instrument responsive to ratio of voltage to current including a voltage winding and a current winding, an auxiliary source of current having connections to said impedance for causing measuring current to traverse said impedance, connections from the voltage winding across said impedance element, and connections having a serial relation to said impedance element for energizing the current winding in proportion to the current traversing said impedance element, each of said instrument connections including isolating units for substantially eliminating load current from the windings of said ratio instrument.

5. In an electrical system including a direct-current circuit traversed by a load current and including a resistance the magnitude of which is subject to variation, apparatus responsive to the magnitude of such resistance, said apparatus comprising a ratio responsive instrument including a voltage winding and a current winding, a local source of alternating current, connections for causing said alternating current to traverse said resistance, connections from the voltage winding across said resistance, and connections having a serial relation to said resistance for energizing the current winding in proportion to the current traversing said resistance, said instrument connections each including electrical isolating units for substantially eliminating direct load current from said windings.

6. In an electrical system including a direct-current circuit traversed by a load current and including a resistance the magnitude of which is subject to variation, apparatus responsive to the magnitude of such resistance, said apparatus comprising a ratio responsive instrument including a voltage winding and a current winding, a local source of alternating current, connections for causing said alternating current to traverse said resistance, connections from the voltage winding across said resistance, and connections having a serial relation to said resistance for energizing the current winding in proportion to the current traversing said resistance, said instrument connections each including a rectifier and electrical isolating units for substantially eliminating direct load current from said windings.

7. In an electrical system including an alternating-current circuit traversed by a load current and including an impedance of magnitude which is subject to variation, apparatus responsive to the magnitude of said impedance, said apparatus comprising in combination with such impedance a ratio responsive instrument including a voltage winding and a current winding, connections from the voltage winding across said impedance, and connections having a serial relation to said impedance for energizing the current winding in proportion to the current traversing said impedance, a local source of direct measuring current and connections for causing said direct measuring current to traverse said impedance, each of said instrument connections including an isolating unit for minimizing the effect of alternating load current in said instrument.

8. An electric arc furnace system comprising in

combination a supply circuit, an arc furnace including an electrode, and an electrode holder connected in the supply circuit, and a protective arrangement responsive to predetermined changes in contact conditions between said electrode and said electrode holder, said protective arrangement comprising in combination with such an electrode and its holder a voltage-current ratio responsive instrument including a voltage winding with a pair of input terminals and a current winding, connections from one of said voltage winding terminals to said electrode and from the other of said terminals to said electrode holder, and connections having a serial relation to said electrode holder supply circuit for energizing the current winding in proportion to the current traversing said circuit.

9. In an electrical system including conductors in contact with connections for causing passage of alternating current, a protective arrangement responsive to predetermined changes in contact conditions, said arrangement comprising in combination with such contact an instrument responsive to ratio of voltage and current including a voltage winding and a current winding, connections including a transformer operatively connecting the voltage winding across the said contact, connections including a rectifier having a serial relation to said contact and said alternating-current connections for energizing the current winding in proportion to the alternating current traversing said contact, and a second rectifier interposed between said transformer and said voltage winding.

10. An electrical system comprising in combination a current-carrying circuit and a protective arrangement therefor, said circuit including a pair of conductors in contact and a useful load supplied by said circuit, said protective arrangement comprising in combination with such contact and connections for causing passage of load current through such contact, a device responsive to ratio of voltage to current having a movable element, said ratio responsive device including a voltage winding and a current winding, connections bridging the voltage winding across said

contact, and connections having a serial relation to said contact for energizing the current winding in proportion to the current traversing said circuit.
